UNITED STATES PATENT OFFICE.

WALTER H. VAUGHAN, OF DETROIT, MICHIGAN.

HEEL.

1,088,115.

Specification of Letters Patent.

Patented Feb. 24, 1914.

Application filed July 14, 1913. Serial No. 778,878.

To all whom it may concern:

Be it known that I, WALTER H. VAUGHAN, a citizen of the United States of America, residing at Detroit, in the county of Wayne 5 and State of Michigan, have invented certain new and useful Improvements in Heels, of which the following is a specification, reference being had therein to the accompanying drawings.

10 This invention relates to cushion heels for shoes and to a disposition thereof whereby a renewable tread surface is obtained that prevents slipping and prolongs the wear of the heel.

15 The invention consists in the matters hereinafter set forth and particularly pointed out in the appended claims.

In the drawings, Figure 1 is a plan view of a heel that embodies features of the invention; and Fig. 2 is a view of the heel partially in inverted side elevation and partially broken away and in section.

Referring to the drawings, a heel body 1 of suitable contour and proportions is 25 formed of rubber or like cushioning material with a series of apertured and screw-threaded anchor plates 2 embedded therein. The face of the heel is recessed above each anchor plate and counterbored to receive a 30 cylindrical plug 3 of rubber or like cushioning material that is secured as by a stud 4 engaging the companion anchor plate. Each plug has an enlarged flanged head 5 with shoulders against the tread of the heel. 35 Because of the flange which is preferably rounded, a cupped or recessed tread face is given each plug which effectively prevents side slipping.

If the outer portions of the plugs toward 40 the margins of the heel wear, they may be readily turned to bring a less worn portion into outer position. As the rims or flanges compress and expand again at each step of the wearer, any dirt that would otherwise 45 be retained is ejected so that the cupping effect, especially on a wet surface is always

present. As the plugs are readily replaced by new ones when fully worn, the body of the heel may be kept intact for an indefinite period. Thus the heel not only has a long 50 life but is effective in preventing slipping and in always presenting a clean surface so that the cushioning effect is not lessened.

Another advantage is the admission of air between the tread of the heel and the pavement, because of the heads of the inserts, so that the unpleasant effect of heat common with rubber heels of the usual type, is obviated.

Obviously, changes in the details of construction may be made without departing from the spirit of my invention and I do not care to limit myself to any particular form or arrangement of parts.

What I claim is:—

1. A cushion heel comprising a body of suitable material having counterbored recesses in the tread face thereof, anchor plates embedded in the body, each adjacent a recess, plugs of cushioning material rotatably 70 inserted in the recesses and studs each securing a plug to its companion anchor plate, the outer faces of the plugs being cupped.

2. A cushion heel comprising a body of suitable material having counterbored recesses in the tread face thereof, anchor plates embedded in the body, each adjacent a recess, plugs of cushioning material rotatably 75 inserted in the recesses, and studs each securing a plug to its respective companion 80 anchor plate, the outer portions of the plugs being enlarged to shoulder against the heel tread and being provided with marginal flanges that compress under weight and eject material from the resultant hollow 85 faces of the plugs.

In testimony whereof I affix my signature in presence of two witnesses.

WALTER H. VAUGHAN.
